MAGNIFYING GLASS

Richard J. Bushon, 1033 E. Las Palmaritas Drive,
Phoenix, Ariz. 85020

Filed Sept. 12, 1969, Ser. No. 19,123

Term of patent 14 years

Int. Cl. D16—08

U.S. Cl. D57—1

FIG. 1 is a perspective view of the magnifying glass showing my new design;

FIG. 2 is a side view of the magnifying glass; and

FIG. 3 is a plan view of the magnifying glass.

I claim:

The ornamental design for magnifying glass, as shown.
